HOLDER FOR FLOWER STEMS OR THE LIKE

Lawrence E. Green, Stinson Beach, and William G. McDermott, Sausalito, Calif., assignors to McDermott & Green, Inc., San Francisco, Calif.

Filed Jan. 5, 1972, Ser. No. 215,705

Term of patent 14 years

Int. Cl. D11—02

U.S. Cl. D35—3

FIG_1

FIG_4

FIG. 1 is a perspective view of a holder for flower stems or the like showing our new design;

FIG. 2 is a top plan view thereof;

FIG. 3 is a bottom plan view; and

FIG. 4 is a side elevational view.

We claim:

The ornamental design for a holder for flower stems or the like, substantially as shown.
